CLAIM

We claim the ornamental design for a support rack, as shown and described.

DESCRIPTION

FIG. 1 is a front perspective of a support rack according to our new design;

FIG. 2 is another front perspective thereof;

FIG. 3 is a top plan view thereof;

FIG. 4 is a bottom plan view thereof;

FIG. 5 is a right elevational view thereof;

FIG. 6 is a left elevational view thereof;

FIG. 7 is a front elevational view thereof; and,

FIG. 8 is a rear elevational view thereof.

The broken lines in the drawings depict portions of the support rack that form no part of the claimed design.
